US00D952702S

(12) **United States Design Patent** (10) **Patent No.:** **US D952,702 S**
Lu (45) **Date of Patent:** **** May 24, 2022**

(54) **REFRIGERATOR FILTER**

(71) **Applicant:** **TIANJIN PREMIUM E-COMMERCE CO., LTD.**, Tianjin (CN)

(72) **Inventor:** **Jun Lu**, Tianjin (CN)

(**) **Term:** **15 Years**

(21) **Appl. No.:** **29/705,781**

(22) **Filed:** **Sep. 16, 2019**

(30) **Foreign Application Priority Data**

Jul. 7, 2019 (CN) 201930358292.X

(51) **LOC (13) Cl.** **15-07**

(52) **U.S. Cl.** ..... **USPC D15/89**
